UNITED STATES PATENT OFFICE.

ORAN W. OTT, OF LOS ANGELES, CALIFORNIA.

FIN-TYPE AIR HEATER.

Application filed May 28, 1927. Serial No. 194,937.

This invention relates to air heaters of the type employing gas for the heating medium, whether the fuel be supplied to the heater as a gas or liquid. In the present instance, 5 the embodiment of the invention illustrated in the drawings, is adapted for the use of the gaseous form of fuel.

An object of the invention is to make provision for a relatively large area of metal to 10 absorb and radiate the heat.

In order to utilize the heating value of fuel to as great a degree as possible, I provide a large number of fins to absorb the heat and radiate the same into the air passages formed 15 by the inter-fin spaces. I provide a number of flues and fins radiating from said flues, the metal that forms the flues and fins being in contact so that the heat will be readily conducted from the flues to the fins for radiation 20 by said fins.

The flues and fins are constructed of sheet metal of any suitable character.

A very important object of the invention is economy in the use of fuel.

25 Another important object is lightness so that the heater can be easily moved from place to place.

Other objects and advantages will appear in the subjoined detailed description.

30 The accompanying drawings illustrate the invention.

Figure 1 is a perspective view of a fin type air heater constructed in accordance with the provisions of this invention.

35 Figure 2 is a perspective view of those elements of the heater that are positioned inside of the housing or body.

Figure 3 is a plan view of the heater, the grating top being omitted.

40 Figure 4 is a fragmental detail, partly in section on the line indicated by 4—4, Figure 3.

Figure 5 is an elevation, partly in section, from the line indicated by 5—5, Figure 4, the 45 upper end of one of the plates being shown as well as the lower end thereof and a portion of said plate being broken away to contract the view.

Figure 6 is a sectional detail view similar 50 to Figure 4 showing a modification of the plates.

Referring to the drawings, there is provided a series or bank of flues, each flue being indicated in its entirety by the character 11. In this particular instance, each flue comprises a pair of oppositely disposed channel-

shaped members 12, the flanges 13 of each of said members being turned away from the flanges of the other member. The flues are partly formed by plates which, in some instances, are interposed between adjacent pairs of the members 12 and, in other instances, are at the outer ends of the endmost pairs of members 12. The plates just referred to have intermediate portions 14 constituting two of the walls of the flues 11, and said plates also have marginal portions 15 that form fins. In this instance, the walls 14 and fins 15 are integral but it is readily understood that they could be of separate construction. The walls 14 and fins 15, with the exception of the two end ones, are interposed between the flanges 13 of adjacent members 12 and are, in fact, clamped between said flanges, by a suitable means, as, for example, bolts or rods 16 which pass through holes 17 in the flanges 13 and through holes 18 in the plates. The rods 16 are screw threaded at their opposite ends as indicated at 19 and the endmost plates are interposed between the end flanges 13 and eye 32 on the rods 16. Engaging the screw threads 19, at each end of each rod, is a nut 21, which, when turned up tight, securely clamps the members 12 and the plates together. *

The flues 11 are positioned upright and each plate has at its lower end a slot 22 to permit of a burner support 23 extending through said slots, as clearly shown in Figure 4. The burner support 23 has a bottom 24, end walls 25 and side walls 26. In this instance, the burner support 23 extends through the lower portions only of the slots 22 so that there is a continuous open space over the burner support 23. A burner 27 is positioned in the support 23 and said burner is spaced a desirable distance from the plates so that there is no danger of burning out said plates. *

Suitable means is provided for supporting the burner support 23 above the level of the floor on which the heater is to rest and, in this instance, said means comprises a pair of eye bolts 28 at each end of the support 23 and the lower ends of each pair of bolts 28 pass through a cross member 29, being secured to said cross member by nuts 30 positioned above said cross member and nuts 31 positioned beneath said cross member. The cross members 29 extend transversely of the burner support 23 and said burner support rests upon said cross members. The rods 16 pass through the eye 32 of the eye bolts 28 and they also pass through holes 33 in the end

walls 34 of a housing or body which is indicated in general by the character 35. The body 35 also comprises side walls 36. In this instance, the body is rectangular and has at 5 its corners supporting legs 37. The end walls 34 are clamped in place on the rods 16 by nuts 38 which are screwed on the threaded portions 19 of the rods. The end walls 34, side walls 36 and legs 37 are all secured together 10 by any suitable means well understood in this art. For example, they may be welded.

The body 35 also comprises a grating top 39. Fuel is supplied to the burner 27 through a pipe 40 which connects at one end to said 15 burner. The other end of the pipe 40 is provided with an air mixer 41 and a valve 42.

The construction and operation of the invention will now be apparent and, in brief, the operation is as follows: Assuming that 20 the fuel has been lighted at the burner 27, the hot combustion gases pass upwardly through the flues 11 heating the thin walls of said flues. The heat is rapidly conducted away from the flue walls by the fins 15 which, 25 as is clearly seen in Figure 3, preferably are spaced from the side walls 36 so as to avoid heating said side walls. The heated fins 15 radiate heat into the inter-fin spaces 43, thus heating the air within said spaces, causing 30 said air to rise and flow through the grating top 39. Cooler air from the floor of the room flows upwardly into the body 35 from the space therebeneath, since said body is open at its bottom.

35 It will be readily understood that the body 35 may, if desired, be omitted and the remaining parts of the heater supported above the floor level by any other suitably constructed support.

40 The elements that are the functional equivalents of those already described are indicated by the same reference characters with the addition of the letter "a." The only difference between the plates in Figure 6 and 45 those in Figure 4 is that the plates in Figure 6 have laterally bent flanges 44 positioned at the upper margins of the slots 22. In this instance, the flanges 44 extend aslant downwardly and outwardly from their fixed ends 50 to their free ends and the free ends extend into the slots of adjacent plates. The purpose of the flanges 44 is to obstruct view of 55 the flame to an observer looking downwardly through the grating top 39. The flanges 44 extend across the flues and the free ends of the flanges are spaced sufficiently from adjacent flanges to permit the gases of combustion to pass between adjacent flanges into the flues.

I claim:

1. A fin type air heater comprising a series of upright flues, two of the walls of each flue being formed of channel-shaped members, fins projecting from the flanges of the channel-shaped members, and a gas burner positioned beneath the flues. 65

2. A fin type air heater comprising a series of upright flues, two of the walls of each flue being formed of channel-shaped members, fins projecting from between the flanges of 70 the channel-shaped members, and a gas burner positioned beneath the flues. 75

3. A fin type air heater comprising a series of upright flues, two of the walls of each flue being formed of channel-shaped members, the intermediate portions of plates forming two other walls of each flue, all but the end plates extending between adjacent flanges of the channel-shaped members, marginal portions 80 of the plates forming outwardly projecting fins, and a gas burner positioned beneath the flues. 85

4. A fin type air heater comprising pairs of spaced channel-shaped members in upright position, plates between adjacent channel-shaped members, rods passing through the flanges of the channel-shaped members, means on the rods to force the channel-shaped members toward one another, and a gas burner positioned beneath the flues. 90

5. A fin type air heater comprising pairs of spaced channel-shaped members in upright position, plates between adjacent channel-shaped members, marginal portions of the plates forming outwardly projecting fins, rods passing through the plates and through the flanges of the channel-shaped members, means on the rods to force the channel-shaped members toward one another, and a gas burner positioned beneath the flues. 95

6. A fin type air heater comprising a series of upright flues, two of the walls of each flue being formed of separate members and the wall of each two adjacent flues being formed by a plate, marginal portions of said plates 105 projecting outside of said first mentioned walls to form heat radiating fins, and a gas burner positioned below the level of the flues.

7. A fin type air heater comprising a series of upright flues, two of the walls of each flue being formed of separate members and the wall of each two adjacent flues being formed by a plate, marginal portions of said plates projecting outside of said first mentioned walls to form heat radiating fins, a housing 115 extending around the flues, and a gas burner positioned in the housing below the flues.

Signed at Los Angeles, Calif., this 19 day of May, 1927.

ORAN W. OTT.
